UNITED STATES PATENT OFFICE.

BERNHARD DREYFUS, OF NEW YORK, N. Y.

DESIGN FOR A PENDANT.

SPECIFICATION forming part of Design No. 15,612, dated December 16, 1884.

Application filed September 17, 1884. Term of patent 7 years.

To all whom it may concern:

Be it known that I, BERNHARD DREYFUS, of the city, county, and State of New York, have invented and produced a new and original Design for Pendants, of which the following is a specification.

This invention relates to a new and ornamental design for pendants.

Reference is to be had to the accompanying drawing, forming a part of this specification, in which a face view of my pendant is shown.

A button or disk, A, is surrounded along its rim by a crescent-shaped piece of chenille, B, and at the thinnest part of the chenille is 15 a slung ruff or tuft, C, and above the said slung ruff or tuft is a loop or hanger, D. F is a button or bead on the middle of each side of the button A, and from the same radial cords or strands G extend to the rim of the 20 said disk or button. Ordinary chenille may

be used for surrounding the button, in place of the crescent-shaped chenille.

I claim—

1. The herein-described design for a pendant, consisting of a button or disk having a central bead surrounded by a piece of chenille provided at its thinnest part with a tuft or slung ruff and a loop, substantially as set forth.

2. The herein-described design for a pendant, consisting of a button surrounded by a crescent-shaped piece, a button or bead being placed on each face of the button, and raised cords or strands extending from the central bead radially to the rim of the button, substantially as shown.

BERNHARD DREYFUS.
